UNITED STATES PATENT OFFICE.

SAMUEL S. WOOD, OF WELLSVILLE, OHIO.

PILING-TABLE FOR METAL SHEETS.

SPECIFICATION forming part of Letters Patent No. 631,841, dated August 29, 1899.

Application filed January 12, 1899. Serial No. 701,928. (No model.)

To all whom it may concern:

Be it known that I, SAMUEL S. WOOD, a citizen of the United States, residing at Wellsville, in the county of Columbiana and State of Ohio, have invented certain new and useful Improvements in Catching, Packing, or Piling Tables for Metal Plates or Sheets; and I do declare the following to be a full, clear, and exact description of the invention, such as will enable others skilled in the art to which it appertains to make and use the same.

My invention relates to a catching, packing, or piling table for receiving and forming even or regular piles of metal plates or sheets as they are delivered from the rolls or roll-train; and the object is to provide a device of this character for expeditiously and economically handling the plates or sheets at this stage of their manufacture.

To this end the invention consists in the construction, combination, and arrangement of the several parts of the device, as will be hereinafter more fully described, and particularly pointed out in the appended claims.

In the accompanying drawings the same reference characters indicate the same parts of the invention.

Figure 1 is a perspective view of my improved catching, packing, or piling table, showing its position with relation to the rolls and also showing one sheet or plate in dotted lines in position on the table. Fig. 2 is a transverse section with a pile of plates or sheets in position on the table. Fig. 3 is a similar view showing the bed of the table and the pile of plates or sheets tilted to a level or horizontal position and with the knee thrown backward out of contact with the aligned edges of the plates.

11 denote the parallel bed-rails, of which there may be a number to correspond to the length of the table, and their upper edges are formed with transverse bearing-notches 2 and 3 to receive the longitudinal parallel bearing-rails 4 and 5, fixed on the under side of the table-bed 6, a third or auxiliary rail 7 being fixed to the under side of the table-bed to act as a brace or stiffener for the table-bed. The upper face of the bed is provided with a longitudinal rail 8, which is intersected by a parallel series of transverse rails 9.

The parallel walls of the longitudinal rail and the transverse rails are provided with a graduated series of transverse aligned orifices 10 to receive a stationary or adjustable bolt, pin, or rivet 11, on which the heel 12 of the foot 13 of the gage-knee 14 is fulcrumed. The outer end of the foot of the knee 14 is formed with a depending toe 15.

16 denotes a removable or stationary pin which rests upon the upper edges of the walls of the rail to form a rest for the free end of the foot and support the arm 17 of the knee at a right angle or any desired angle to the table-bed. In the case of the side knees this pin 16 is prevented from sliding down the inclined face of the rails by the toe 15, and in the case of the end knee the pin is provided with an enlarged head *a*, which rests against the rail 8 to prevent the pin from sliding under the knee.

I do not confine myself to the adjustable and removable knees, for, if desired and when an advantage, a stationary or fixed knee can be used.

If desired, the table can be inclined in one or more directions at the same time—for instance, by placing the bed-rails 11 on different levels. This will sometimes be found an advantage.

This table may be conveniently placed wherever it is desired to pile up a quantity of sheets, and in Fig. 1 I have shown it placed near the rolls 18, from which a sheet or plate is taken by an attendant and drawn along the inclined face of the table until the forward end of the sheet comes in contact with the end knee, and upon the sheet or plate being released it slides by gravity down the inclined face of the table until its lower edge rests against the side knees. The succeeding sheets are treated in the same manner until a sufficient pile has been formed on the table. The table is now tilted to a horizontal position, as shown in Fig. 3, and the pins 16 removed from under the outer ends of the knees, which allows that end of the knee to fall so that its toe 15 rests upon the lower face of the rail. This throws the arm 17 away from the contiguous aligned edges of the sheets or plates. The sheets or plates now remain on the table in a pile with their contiguous edges aligned.

in a true plane and in position to receive the crab-hoist or grapple of the crane, which now lifts the sheets or plates for transportation.

It will be understood that various changes in the form, proportion, and the minor details of construction may be resorted to without departing from the spirit or sacrificing any of the advantages of this invention.

Having thus described the invention, what is claimed, and desired to be secured by Letters Patent, is—

1. In a table of the class described, the combination with the fixed bed-rails, of a table fulcrumed on said rails and adapted to be tilted from a horizontal to an inclined position, and a series of gage-knees longitudinally and laterally adjustable on the working face of said table, substantially as and for the purpose set forth.
2. In a table of the class described, the combination with the tilting bed, and a series of rails projecting above the face of the table

to receive the sheets or plates, of a series of knees adjustably secured to said rails, substantially as and for the purpose set forth. 25

3. In a table of the class described, the combination with the notched bed-rails, of the table-bed, the longitudinal parallel bearing-rails fixed to the under side of said bed and adapted to support the table in either a horizontal or inclined position, the longitudinal and the transverse rails fixed to the upper face of said table-bed, and a series of gage-knees adjustably secured to said longitudinal and transverse rails, substantially as and 30 35 for the purpose set forth.

In testimony whereof I have hereunto set my hand in presence of two subscribing witnesses.

SAMUEL S. WOOD.
